UNITED STATES PATENT OFFICE

ANGELO S. FERRIERA, OF SAN JOSE, CALIFORNIA

DESIGN FOR AN ICE-CREAM CONFECTION

Application filed July 24, 1929. Serial No. 32,196. Term of patent 7 years.

To all whom it may concern:

Be it known that I, ANGELO S. FERRIERA, a citizen of the United States, residing at San Jose, in the county of Santa Clara and State of California, have invented a new, original, and ornamental Design for Ice-Cream Confection, of which the following is a specification, reference being had to the accompanying drawing, forming a part thereof.

In the drawing:

The confection comprises a solid mass of ice cream molded as shown.

I claim:

The ornamental design for an ice cream confection, as shown and described.

ANGELO S. FERRIERA.
